UNITED STATES PATENT OFFICE.

FRED A. BATCHELDER, OF CAMBRIDGE, MASSACHUSETTS.

CAN-RESHAPING MACHINE.

1,151,995.

Specification of Letters Patent. Patented Aug. 31, 1915.

Application filed January 4, 1915. Serial No. 346.

To all whom it may concern:

Be it known that I, FRED A. BATCHELDER, a citizen of the United States, residing at Cambridge, in the county of Middlesex and State of Massachusetts, have invented certain new and useful Improvements in Can-Reshaping Machines, of which the following is a specification, reference being had to the accompanying drawings, forming part thereof.

This invention has reference to improvements in machines for reclaiming cans which in use have become dented or distorted in shape and particularly when the dimensions of said cans have been reduced by indentations.

The main object of the invention is to so construct a machine of the nature herein described that the wall of a sheet metal can may be reshaped without materially changing its dimensions.

Another object of the invention is to provide a can reshaping machine in which the introduction or removal of the can is facilitated.

Other objects of the invention will appear from the following description.

The invention consists in the novel arrangement of the reshaping rolls and the parts coöperating therewith.

The invention also consists in such other novel features of construction and combination of parts as shall hereinafter be more fully described and pointed out in the claims.

Figure 1, represents a side elevation of the improved can reshaping machine, parts of the same being broken away. Fig. 2, represents an end or plan view of the improved machine, the two main rolls being shown in section as on line 2-2 of Fig. 1.

Similar characters of reference designate corresponding parts throughout.

Cans of various kinds after some little use become misshapen by reason of the indentation of their walls from blows. In most cases the use of cans having such indentations reduces materially the dimensions of the cans and, in all cases, the use of cans having indentations is objectionable. In actual practice it has been found difficult to smooth out the sheet metal wall of a can having indentations without so upsetting the material of the wall that the dimensions of the can operated on are changed, usually by reducing the diameter of the can somewhat.

In carrying my invention into practice I provide a machine in which the reshaping of the wall of a can, to flatten or smooth out indentations therein, is effected by rolls and in such manner that the tendency of the wall of the can to contract is offset by the exertion continually of a slight outward strain on said wall during the rolling process and I provide means for facilitating the operation on the can.

In the embodiment of my invention disclosed in the accompanying drawings 5 indicates a substantially rigid base or supporting member for the operating mechanism. This base 5 is shown in the drawings as extending vertically and as adapted to be secured to another upright member but, if preferred, such base 5 may extend horizontally. Mounted on said base 5 are the plates 6 and 7 of which plate 6 has the frame 8 having the pressure screw 9 and the bearing blocks 10 and 11 the latter of which is centered in said frame 8 by the side bearing screws 12 and has a socket to receive the pressure screw 9.

Plate 7 has the frame 13 having the adjusting screw 14 and the side bearing screws 15, 15. Pivotedly connected with the screw 14 is the rigid link 16 which in turn is pivotally connected by the link 17, having the lever handle 18, with the stem 19 of the shaft bearing member 20 which latter is centered between the side screws 15, 15 but is capable of movement in line with its stem 19 when the latter is moved by the swinging of link 17 effected by means of its lever handle 18. Said frame 13 is provided with the cross bar 21 which is adapted to limit the endwise movement of long cans and said frame 7 has the bearing member 22 which coöperates with a somewhat similar member 23, located on plate 7 at a distance from the frame 13, to rotatably support the small rolls 24, 24, having grooves as 25. On said plate 7 are mounted the pairs of arms 26, 26 having at their upper ends the rails 27, 27 mounted for adjustment relative to the diameter of a can to be received therebetween.

Journaled in the bearing blocks or members 10, 22 and 23 is the main roll 28 having the flange 29 and the circumferential grooves 30 and 31, and the gear 32. Provision is made for rotating this roll 28 in any suitable manner, herein shown as the pulley 33 mounted on said roll 28 and adapted to be

driven by the belt 34 from any suitable driving mechanism which is not shown as it constitutes no part of the present invention. The main pressure roll 35 is journaled in the bearing blocks or members 11 and 20 and is preferably driven by the engagement of its gear 36 with the gear 32 of the roll 28.

By the swinging of the lever handle 18 from the position shown in Fig. 1 the link 17 is swung to relieve the pressure exerted thereby on the bearing member 20, through its stem 19, and to draw said bearing member 20 and the pressure roll 35 away from roll 28 sufficiently to permit the can C to be placed in position over the end of the pressure roll 35 with its exterior annular rib c and its bottom joint c' received in the grooves 30 and 31 respectively of the roll 28 which grooves constitute clearances for said parts c and c'. The rib c of said can C is also received by the grooves as 25 of the rolls 24, 24. Such position of the can C is facilitated by the rails 27, 27 which when adjusted to bear slightly against the can also assist in preventing lateral movement of the can. Lever handle 18 is now swung to the position shown in Fig. 1 and, by such movement, link 17 is brought into alignment with link 16 and stem 19 and bearing member 20 with its roll 35 is forced toward roll 28 and said roll 35, operating against the inside of the wall of can C, forces said wall into contact with the periphery of roll 28 between the rolls 24, 24. In such position the flange 29 overlaps the bottom end of can C and prevents the endwise movement of said can in one direction. Rolls 28 and 35 are now caused to rotate and said rolls being frictionally engaged 40 with the wall of the can C cause said can to rotate and at the same time compress and smooth out any indentations or rough portions in the wall of the can while the rolls 24, 24 act as rotatable guides for the can and so

sustain the wall of the can that the pressure 45 of roll 35 tends to press the wall of the can radially. After such reshaping of the can C, the lever handle 18 is swung to the release position and the can is removed endwise from the machine.

Having thus described my invention I claim as new and desire to secure by Letters Patent.

1. A can reshaping machine comprising a base, frames on said base having bearings, 55 a pressure roll journaled in said bearings and having a peripheral flange at one end and a pair of grooves, a second pressure roll journaled in bearing members carried by said frames, one of said latter bearings being movable, means for moving said latter bearing and its roll toward and from said first roll, means for rotating one of said rolls, and a pair of guide rails adjustably mounted at the sides of the machine and 60 adapted to receive between them a can to be operated on.

2. A can reshaping machine comprising a base, frames on said base having bearings, 70 a pressure roll journaled in said bearings and having grooves to receive exterior projections of the can under operation, a pair of grooved rolls journaled in bearings at the sides of and above the axis of said first pressure roll, a second roll journaled in 75 bearings of said frames, one of which latter bearings being movable, adjustable centering means for said latter bearing, a rigid stem extending from said movable bearing, a link adjustably mounted relative to said stem, 80 a second link pivotally connected with said first link and with said stem and having a lever, and means for operating one of said pressure rolls.

FRED A. BATCHELDER.
